UNITED STATES PATENT OFFICE.

HENRY HONECK, OF BATAVIA, NEW YORK, ASSIGNOR TO THE BATAVIA AND NEW YORK WOOD WORKING COMPANY, OF BATAVIA, NEW YORK.

DESIGN FOR A PHONOGRAPH-CASE.

56,614.

Specification for Design.

Patented Nov. 16, 1920.

Application filed October 31, 1919. Serial No. 334,867. Term of patent 3½ years.

To all whom it may concern:

Be it known that I, HENRY HONECK, a citizen of the United States, residing at Batavia, in the county of Genesee and State of New York, have invented a new, original, and ornamental Design for a Phonograph-Case, of which the following is a specification.

The accompanying drawing shows a front view of a phonograph case embodying the design.

I claim.

The ornamental design for a phonograph case as shown.

HENRY HONECK.
